(57) **CLAIM**

I claim the ornamental design for a ring, as shown and described.

DESCRIPTION

FIG. 1 is a perspective view of a ring, showing the new design; FIG. 2 is a front elevational view thereof; FIG. 3 is a rear elevational view thereof; FIG. 4 is a right-side elevational view thereof; FIG. 5 is a left-side elevational view thereof; FIG. 6 is a top plan view thereof; and, FIG. 7 is a bottom plan view thereof.

The broken lines showing a gemstone in FIGS. 1-6 represent environmental matter, and form no part of the claimed design.
